US0D1048457S

(12) **United States Design Patent** (10) **Patent No.:** **US D1,048,457 S**
(45) **Date of Patent:** **** Oct. 22, 2024**

(54) **DETECTOR PEN**

(71) Applicant: **ASSURE TECH. (HANGZHOU) CO., LTD.**, Zhejiang (CN)

(72) Inventors: **Shisheng Ling**, Hangzhou (CN); **Lei Yao**, Hangzhou (CN)

(73) Assignee: **ASSURE TECH. (HANGZHOU) CO., LTD.**, Hangzhou (CN)

(**) Term: **15 Years**

(21) Appl. No.: **29/789,996**

(22) Filed: **Oct. 28, 2021**

(30) **Foreign Application Priority Data**

Oct. 18, 2021 (CN) 202130682433.0

(51) **LOC (14) Cl.** **24-02**

(52) **U.S. Cl.**

USPC **D24/224**

(58) **Field of Classification Search**

USPC D24/222-226; D9/216, 520-521;
D10/81

(57) **CLAIM**

The ornamental design for a detector pen as shown and described.

DESCRIPTION

FIG. 1 is perspective view of a detector pen showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 6 Drawing Sheets
